UNITED STATES PATENT OFFICE

170,071

NAPKIN OR SIMILAR ARTICLE

Roy J. Vernon, Minneapolis, Minn.

Application December 10, 1952, Serial No. 22,610

Term of patent 7 years

(Cl. D59—2)

To all whom it may concern:

Be it known that I, Roy J. Vernon, a citizen of the United States of America, residing in the county of Hennepin, State of Minnesota, have invented a new, original, and ornamental Design for a Napkin or Similar Article, of which the following is a specification, reference being had to the accompanying drawing forming a part hereof, in which:

The figure is a plan view of a napkin or similar article showing my new design.

I claim:

The ornamental design for a napkin or similar article, substantially as shown.

ROY J. VERNON.
